UNITED STATES PATENT OFFICE.

CHRISTIAN N. SMITH, OF DAYTON, OHIO.

MIDDLING-PURIFIER.

SPECIFICATION forming part of Letters Patent No. 337,207, dated March 2, 1886.

Application filed February 14, 1885. Serial No. 155,916. (No model.)

To all whom it may concern:

Be it known that I, CHRISTIAN N. SMITH, a citizen of the United States, residing at Dayton, in the county of Montgomery and State of Ohio, have invented certain new and useful Improvements in Middlings-Purifiers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a side view of my purifier. Fig. 2 is a cross-sectional view of the same, taken on the lines *xx* of Fig. 1. Fig. 3 is a view of the feed end of the machine, partly in section. Fig. 4 is a horizontal longitudinal sectional view taken on the lines *yy* of Fig. 1. Figs. 5 and 6 are different views of the feeder attached to the screen-frame B. Fig. 7 is a detail plan view of the screen-frame B, showing some of the mechanism for transversely vibrating it. Figs. 8, 9, 10, 11, 12, 13, and 14 are detail views; and Fig. 15 is a vertical central longitudinal sectional view.

This invention relates to improvements in middlings-purifiers; and its objects are to accurately regulate the draft that passes up through the screen and carries away the dust; to feed the screen regularly; to readily adjust the tension of the screen-cloth and clean the screen efficiently.

Reference being had to the accompanying drawings and to the letters of reference marked thereon, A represents the general frame of the machine, having on top the exhaust-fan *a*, immediately below which is the draft-chamber *a'*, extending longitudinally above the separating-chamber *a''*.

B is the screen-frame, of rectangular form, and extending longitudinally in the main frame below the separating-chamber, which extends longitudinally in the main frame and opens below into the screen-frame, from the sides of which its sides rise vertically for a short distance, and then converge upward and inward to the bottom of the draft-chamber, opening centrally therein for its entire length.

The separating-chamber is practically continued into the draft-chamber by the longitudinal valves *b b*, arranged in opposite pairs above its opening, and adapted to be opened more or less widely apart by means of the rods *b'* and links *b''*, according to the amount of draft desired within the separating-chamber. The rods *b'* pass through the upper part of the main frame, and are arranged to hold the valves in the desired position. The screen-frame *B* is hung by means of the rods or straps *b''*, pivoted at their lower ends to blocks or studs fixed to the sides of said frame and the curved slotted rods or brackets *b'*, which are fixed to the main frame, and have the upper ends of the rods *b''* adjustably pivoted within their slots by bolts and washers, as shown. When the upper ends of said rods are adjusted in the ends of the slots nearest the receiving end of the machine, the screen will fall during all its motion toward that end, and will carry the material toward the discharge end during all the reverse motion. In this position the rods will be inclined and the travel of material will be most rapid. The travel will become less rapid as the ends of the rods *b''* are moved in the slots toward the discharging end, and when in the ends of the slots nearest thereto the rods *b''* will swing equally to each side of a perpendicular line as the screen frame moves in either direction.

C is the conveyer-chamber below the screen-frame, having its upper part hopper-shaped to collect from the latter, and provided with the longitudinal conveyers *c c*, constructed in the usual manner and actuated by suitable mechanism conjointly with the screen-frame and blower.

D is a shaft having bearings in brackets or supports fixed in proper position to the front of the main frame, and *d d* are similar eccentrics fixed upon said shaft and connected with the bottom of the screen-frame at the sides thereof by the eccentric-rods *e e*, as shown, so that when the shaft *D* is rotated the screen-frame is reciprocated. The shaft *D* has pulleys fixed at proper points upon it, by means of which and suitable belts the pulleys that rotate the fan-shaft and the shafts of the conveyers are driven.

d^2 is the discharge-spout from the tail end of the screen-frame.

E is the feeder, attached to the front of the main frame in a suitable position, and moved 5 transversely across the same by means of the bell-crank e and link e^2 . The feeder is triangular in outline, and is situated immediately within the separating-chamber, with its base over the front portion of the screen. The 10 bell-crank has one arm pivoted to the feeder, its angle pivoted to a bracket fixed to a cross-bar of the main frame, and the other arm pivoted to the link e^2 , which connects with the front cross-bar of the screen-frame. Thus the 15 longitudinal motion of the latter gives the feeder a lateral motion. The feeder is fed in front by a proper hopper, and feeds the screen through an opening, e^3 , in the cross-plate e^4 .

F F are opposite longitudinal recesses in 20 the side beams of the screen-frame. These recesses are on the inner surfaces of the beams, and are covered by the longitudinally-slotted boards f f.

G is the screen-cloth, the side edges of which 25 pass through the slots in the boards f into the recesses F and are formed into longitudinal pockets g. To retain the screen in place, lateral strips or rods g' g' are passed into these pockets, and to tighten it laterally larger 30 strips are inserted into the same. The end edges of the screen are tacked to movable cross-bars g² g², which have their ends sliding in recesses in the screen-frame, and are drawn apart and the screen stretched longitudinally 35 by means of the screws g³ g³.

H are parallel longitudinal cleaning-cords running below the screen, with their front ends secured to the cross-bar h of the screen-frame, near the front of the same, and thence 40 running over a guide-piece, hereinafter described, near the rear of the screen-frame.

I I are standards having their lower ends bolted to the inside of the rear of the main frame, behind the guide-piece. The upper 45 end of each standard curves forward, and has pivoted upon it a piece, i, for a purpose hereinafter explained.

J is a transverse bar bolted to the upwardly-extending arms of the pieces i i, and having 50 fixed to it the guide-piece j, over which the cleaning-cords pass.

K is a shaft oscillating in bearings in brackets depending from the sides of the screen-frame near its rear end. The said shaft passes 55 through the recesses k in the downwardly-extending arms of the pieces i i, and has secured to it the rear ends of the cords H. When the screen-frame moves forward, the bearings of

the shaft K are also moved forward in front of the pivots of the pieces i. The upper arms of 60 said pieces and the bar J and guide-pieces j are consequently turned backward, and the cords H are stretched and made tense with somewhat of a jerk. When the screen-frame moves backward, the pieces i turn in the opposite direction and the cords H are loosened. 65

The main object of the construction of the chamber a² is to equalize the action of the air over the whole screen-cloth. This is accomplished by having the valves situated centrally 70 and equal amounts of air entering from both sides. Thus all points of the valves are equally distant from the air-entrances, and equal amounts of air pass through all points of the cloth. The proper draft is attained by 75 means of the valves b, which, when the draft is too strong, are partially closed by means of the rods b, and partially opened when the draft is too weak.

Having described my invention, what I 80 claim, and desire to secure by Letters Patent, is—

1. In a middlings purifier, the combination, with the main frame A, longitudinally-reciprocating screen-frame B, and separating-chamber 85 a², of the draft-chamber a¹, valve b, rods b', links b'', and a suitable exhaust-fan above the draft-chamber, substantially as specified.

2. In a middlings-purifier, the combination of the screen-frame having its side bars grooved 90 upon their inner faces, the bolting-cloth having tubular edges and the boards f, partially overlapping the grooves, so as to confine the rods and cloth, substantially as specified.

3. In a middlings-purifier, the combination, 95 with the main frame A, screen-frame B, cleaning-cords H, and shaft K, oscillating in bearings in brackets depending from the sides of the screen-frame, near its rear end, of the standards I, having the pieces i pivoted upon them, transverse bar J, and guide-pieces j, substantially as specified.

4. In a middlings-purifier, the combination of the reciprocating bolt, the shaft K, journaled upon the screen-frame, near its outer 105 end, the levers i, fulcrumed in fixed supports, the bar J, and the cords H, attached at one end to the screen-frame and at the other to shaft K, and passing over a bar, J, substantially as specified.

In testimony whereof I affix my signature in presence of two witnesses.

CHRISTIAN N. SMITH.
